UNITED STATES PATENT OFFICE.

FREDERICK E. CARLSON, OF NEW BRITAIN, CONNECTICUT, ASSIGNOR TO LANDERS, FRARY & CLARK, OF NEW BRITAIN, CONNECTICUT, A CORPORATION OF CONNECTICUT.

VACUUM-BOTTLE.

1,186,544.

Specification of Letters Patent. Patented June 13, 1916.

Original application filed February 26, 1913, Serial No. 750,713. Divided and this application filed August 7, 1913. Serial No. 783,477.

To all whom it may concern:

Be it known that I, FREDERICK E. CARLSON, a citizen of the United States, and a resident of New Britain, in the county of 5 Hartford, State of Connecticut, have invented certain new and useful Improvements in Vacuum-Bottles, of which the following is a specification.

The object of the invention is to produce 10 an article of the character described having features of novelty and advantage, and especially as regards the sealing of the neck of the bottle in the cap and the support of the bottle within the casing.

15 The subject matter of this application is divided out of a former application, S. No. 750,713, filed Feb. 26, 1913.

In the drawings—Figure 1 is a central vertical section of a device of the class specified in which my invention is embodied, the bottle being shown in side elevation. Fig. 2 is a detail side view of the support shown in Fig. 1. Fig. 3 is a top view thereof. Figs. 4 and 5 are detail views of the sealing device.

Referring to the drawings, *a* denotes the casing which is provided with a disengagable cap in order to permit of the insertion and withdrawal of the bottle.

30 *b* is the bottle, the neck of which preferably projects slightly through an aperture in the end of the cap.

c is a sealing ring located in an annular groove *d* adjacent the aperture in the end 35 of the cap and bearing on an inclined surface of the neck of the bottle. This sealing ring comprises a curved wire spring *c'* with its ends spaced apart, covered by a tubular cushion *c''* of rubber or other resilient material, the ends of which abut to form a complete circle. This provides a resilient gasket or packing having a spring core and of such size that it fits in the annular groove *d* and bears upon the neck of the bottle when the parts are properly assembled, providing a cushion between the glass and the metal and a liquid-tight packing.

Located within the casing is a combined holder and spacer comprising a resilient support such as the spring *e* (Figs. 1 and 2), a base *f* having spring fingers *f'* upon which the bottom of the bottle rests, and upwardly-extending longitudinally-bowed arms *g*, the ends of which are split and rest against the

walls of the casing, and the bowed parts engaging the sides of the bottle.

In order to connect the cap with the body of the casing the spring *e* must be compressed, and it will thus be seen that the bottle is held between the sealing ring and the spring, both being resilient devices and under compression. The upstanding arms support the bottle yieldingly against too great displacement. As a result of this construction it will be seen that the bottle is suspended within the casing against movement in any direction by resilient devices, constituting an extremely effective protection against damage to this very fragile structure. The sealing device at the neck of the bottle also constitutes a liquid-tight joint so that any drip down the outside of the bottle cannot run down into the casing.

I am aware that various changes in construction may be made without departing from the spirit of the invention.

I claim as my invention:

1. The combination with a casing including its cap, and a bottle, of a combined holder and spacer for said bottle comprising a resilient support, a base secured at the upper end thereof and longitudinally-bowed arms upstanding from said base and interposed between the walls of the bottle and the casing.

The combination with a casing including its cap, and a bottle, of a plurality of resilient spacers located between the sides of said bottle and casing, and a resilient support interposed between the lower ends of said spacers and the bottom of said casing.

3. The combination with a casing including its cap, and a bottle, of a combined holder and spacer for said bottle comprising a resilient member resting on the bottom of the casing, a base secured to the top of said resilient member adapted to receive the end of the bottle, a resilient member located between the neck of the bottle and the opposite end of the casing, and a plurality of longitudinally-bowed resilient arms upstanding from said base and located between and in contact with the walls of said bottle and casing.

4. The combination with a casing including its cap, and a bottle, of a combined holder and spacer for said bottle comprising a spring support, a base mounted at the

top thereof, spring fingers on the base adapted to receive the end of the bottle, and longitudinally bowed arms upstanding from the edge of said base and interposed between 5 and in contact with the walls of the bottle and casing.

5. A casing, a vessel of fragile material located therein, and cushioning means between said casing and vessel, said means comprising 10 a plurality of circumferentially-spaced longitudinally curved strips of resilient material, each strip adapted to contact at non-opposite points with said casing and vessel, said strips being free and 15 unconnected with one another throughout

their length, and adapted for action independently of one another.

6. A casing and a vessel of fragile material located therein, resilient means located between the bottom of the vessel and the bottom of the casing, cushioning means arranged between the wall of the vessel and the wall of said casing extending longitudinally thereof, said means being spaced circumferentially and unconnected with one 20 another throughout their length. 25

FREDERICK E. CARLSON.
